(57) **CLAIM**

The ornamental design for lighting fixture, as shown and described.

DESCRIPTION

FIG. 1 is an isometric view of a first embodiment of a lighting fixture according to the design;

FIG. 2 is a side view of the lighting fixture of FIG. 1;

FIG. 3 is an isometric view of a second embodiment of a lighting fixture according to the design; and,

FIG. 4 is a side view of the lighting fixture of FIG. 3.

The broken lines in the drawings illustrate portions of the lighting fixture and do not form part of the claimed design.
